UNITED STATES PATENT OFFICE.

JOSEPH B. DEPRIEST, OF MANASSA, COLORADO.

RAILROAD-TIE.

No. 888,227.

Specification of Letters Patent.

Patented May 19, 1908.

Application filed July 8, 1907. Serial No. 382,670.

To all whom it may concern:

Be it known that I, JOSEPH B. DEPRIEST, a citizen of the United States, residing at Manassa, in the county of Conejos, State of Colorado, have invented certain new and useful Improvements in Railroad-Ties; and I do hereby declare the following to be a full, clear, and exact description of the invention, such as will enable others skilled in the art to 10 which it appertains to make and use the same.

This invention relates to railroad ties and more particularly to that class which are of composite structure and which embody rail 15 securing devices.

The primary object of the invention is to provide a tie of this class in which the rail securing devices, being embedded in the tie, are so spaced as to properly align the rails 20 held thereby. Furthermore these rail securing devices are flush with the upper and under faces of the tie and consequently there is no likelihood of their being injured during the transportation of the tie.

25 In the accompanying drawings, Figure 1 is a side elevation of a tie embodying my invention, Fig. 2 is a vertical longitudinal sectional view in detail through one end of the tie and a rail supported thereby, and, Fig. 3 30 is a top plan view of one end of the tie with the rail removed.

In the drawings the numeral 5 denotes the tie preferably composed of cement, sand and gravel and 6 a rail supported thereon.

35 The device for securing the rail upon the tie and embodying my invention comprises in part a U-shaped member including spaced portions 7 and a connecting portion 8 the former being spaced apart a distance equal 40 to the width of the base flange of the rail 6. The said element of the fastening device is embedded in the tie with the upper ends of its spaced portions 7 flush with the upper face of the tie and its connecting portion 8 45 embedded in the under face of the tie and

flush therewith as clearly shown in Fig. 2 of the drawings. Each of the portions 7 is provided with a longitudinally extending bore 9 which is threaded and which opens through the upper end of its respective member. 50 Screw bolts are employed in connection with this element of the device for holding the rail upon the tie and each of these bolts includes a threaded shank 10 which is screwed into the corresponding bore 9 and an integral 55 annular rail-flange-engaging collar portion 11 which has a concaved under surface 12 of the same contour as the upper face of the outer edge portions of the rail base flange, it being understood that when the bolts are screwed 60 into the bores as stated above the said collars will bear upon the said outer edge portions of the base flange of the rail and hold the same to the tie. In order that the screw bolts may be screwed into the bores as stated, a 65 square head 13 is formed integral with the upper face of each of the collars or heads 11 so that a wrench may be engaged therewith.

From the foregoing description of my invention it will be observed that while the 70 rails are securely held in place upon the ties embodied in my invention, they may be readily removed should it become necessary by merely unscrewing the screw bolts.

What is claimed, is—

75 A tie comprising a plastic body, a U shaped member cylindrical throughout embedded in said body adjacent each end thereof, the arms of each U-shaped member being directed upwardly through the body with 80 their ends flush with the upper face thereof, the said arms being formed with threaded sockets, and rail flange engaging bolts screwed into the sockets.

In testimony whereof, I affix my signature, in presence of two witnesses.

JOSEPH B. DEPRIEST.
